UNITED STATES PATENT OFFICE.

JOHN WILSON BROWN, JR., AND HERBERT W. YEAGER, OF PHILADELPHIA, PENNSYLVANIA, ASSIGNORS TO THE ENTERPRISE MANUFACTURING COMPANY OF PENNSYLVANIA, OF PHILADELPHIA, PENNSYLVANIA, A CORPORATION OF PENNSYLVANIA.

POLISHING-MACHINE.

SPECIFICATION forming part of Letters Patent No. 707,819, dated August 26, 1902.

Application filed May 16, 1902. Serial No. 107,653. (No model.)

To all whom it may concern:

Be it known that we, JOHN WILSON BROWN, Jr., and HERBERT W. YEAGER, citizens of the United States, and residents of Philadelphia, Pennsylvania, have invented certain Improvements in Polishing-Machines, of which the following is a specification.

Our invention relates to certain improvements in machines for polishing or buffing the edges of sad-irons and like articles.

The object of our invention is to so construct the machine that a number of sad-irons can be mounted on chucks on a rotating frame, so that as the sad-irons are brought into contact one after another with the polishing-wheel the edges of the irons will be polished, as fully described hereinafter. This object we attain in the following manner, reference being had to the accompanying drawings, in which—

Figure 1 is a side view of sufficient of the improved polishing-machine to illustrate the invention. Fig. 2 is a plan view. Fig. 3 is a vertical sectional view on the line 3 3, Fig. 25 1. Fig. 4 is a sectional plan view on the line 4 4, Fig. 1. Fig. 5 is a sectional plan view on the line 5 5, Fig. 1; and Fig. 6 is a view showing the clutch mechanism for engaging the sad-iron.

30 A is the base of the machine. Mounted on this base is a carriage B, supported in the present instance on a series of rollers a, as clearly shown by dotted lines in Fig. 1, and on this carriage is a slide B', having standards b, carrying at their upper ends the bearings b' for the shaft C. On the shaft is a step-pulley C' and on the outer end of the shaft is a buffering-wheel C², made up of a series of sheets of fabric held together by 35 means of the clamp-plates c c, mounted on the shafts C.

40 B² is an adjusting-screw having its bearings in a bracket b² at one end and arranged to pass through a nut on the slide B'. By 45 turning this hand-wheel the slide can be adjusted on the carriage, so as to adjust the buffering-wheel toward and from the work.

D is a lever pivoted at d to the frame of the

machine and connected by a link d' at one end to a stud on the carriage B. The other 50 end of the lever is provided with a roller d², which is actuated by a cam on a part of the machine, so as to move the carriage, and consequently the buffering-wheel, to accommodate irregular work.

55 d³ is a weight attached to a chain d⁴, connected to the outer end of the carriage B, and this chain passes around the wheel a', mounted in bearings in the base A of the machine, so that the tendency of the weight is 60 to move the carriage away from the work; but it is drawn toward the work by the mechanism actuating the lever D, described above.

We will now describe the carrier for holding the sad-irons and the mechanism connected 65 therewith.

A' is a bracket extending in the present instance from one corner of the base A, and mounted in this bracket is a fixed standard E. The lower portion of the standard is tapered to fit the tapered socket a² in the bracket, and the standard is held in place by a nut e.

70 Mounted between the head e' on the upper end of the standard E and a bearing e² on the bracket A' is a carrying-frame F. This carrying-frame has channels f f' for the reception of bearing-balls, which are mounted between the carrying-frame and the portions e², as indicated in Fig. 1.

75 G is a shaft having its bearings in a bracket A' and having a driving-wheel g to receive a belt from any suitable power-shaft. On the shaft G is a worm g', which meshes with a worm-wheel h on a stud H, projecting from the 80 bracket A', and secured to hub of this worm-wheel h is the disk I of a star-wheel lock-gear. (Shown clearly in Fig. 5.) On an extension of this disk is a pin i, which works in radial slots i' in the star-wheel I', secured to the 85 lower portion of the carrier F, so that on each revolution of the disk I the star-wheel and the carrier in the present instance will be moved one-fifth of a revolution. In the present instance there are five spindles J, mounted in 90 bearings f² of the carrier F, and by having a 95

star-wheel of five slots it will bring the several spindles into proper relation with the buffing-wheel. On the lower end of each spindle is a worm-wheel j , which is brought 5 into mesh with a worm k on the shaft K, geared to the shaft G through a pinion k' and gear-wheel g^2 , so that when the carrier is moved to bring one of the spindles in proper position in respect to the buffing-wheel it is 10 rotated by the mechanism above described.

On the upper end of the spindle J is a bevel-wheel j' , which meshes with a bevel-wheel l on a hollow shaft L mounted in the head F', secured to a projection F² of the carrier F. On the end of the shaft L is pivoted 15 a clutch member l' , which is arranged to engage the cross-bar of the sad-iron, as clearly shown in Fig. 6. A rod l^2 extends through the shaft L, being connected at one end to 20 the clutch member l' , and has a collar l^3 at the other end. Resting in a groove in this collar is one arm of a releasing-lever l^4 , Fig. 3, pivoted to the head F', so that on depressing the long arm of this lever the clutch can 25 be withdrawn to free the sad-iron. A spring back of the clutch will tend to return the clutch to its original position when the lever is released, so that a sad-iron to be ground can be simply forced into place the same as 30 in the ordinary detachable-handle sad-iron. The construction of this clutch will vary according to the style or the design of the iron, and if another object is to be ground it will be made to couple properly to the object.

35 It will be seen that when the carrier is brought into position and the edge of the iron is in line with the buffing-wheel, as shown in Fig. 2, the shaft K will slowly drive the spindle J, which will in turn drive the shaft L 40 and turn the iron on edge, so that the entire edge will come in contact with the buffing-surface. In order to allow for the irregularity of the said iron a cam M is secured on each spindle J, and this cam acts against a 45 roller d^2 on the lever D, described above. This cam as the spindle revolves will move the carriage B and the buffing-wheel toward and from the work, according to the cut of the cam, so that the buffing-wheel will always 50 have a fixed relation to the sad-iron or other article to be polished. The cams and the lever are clearly shown in Fig. 4.

The operation of the machine is as follows: When the parts are in operative position, the 55 irons are clutched to the several heads, as shown, and motion is imparted to the machine. The star gear-wheel moves the carrier, so as to bring one of the spindles in line with the buffing-wheel, when it will be locked in this 60 position until during a certain portion of the revolution of its driving-shaft, and during this time the spindle J is driven slowly and motion is imparted to the sad-iron, so as to present its entire edge to the action of the 65 buffing-wheel. The cam M on the spindle will move the buffing-wheel toward and from the work as the work is rotated. Thus the buff-

ing-wheel will always bear the same relation to the work. After the buffing-wheel has completed its work the carrier is moved one-fifth 70 of a revolution by the star-wheel, moving the polished iron to one side and moving into position one that is to be polished. The operator simply removes the polished iron and places another in its stead, and the work is 75 thus continued without interruption.

We claim as our invention—

1. The combination in a machine for polishing the edges of sad-irons and other objects, of a polishing-wheel, a carrier, a spindle 80 mounted in bearings in the said carrier, means for turning the carrier, means for turning the spindle, a shaft geared to the spindle, and a chuck carried by said shaft for engaging the article to be polished, substantially as described. 85

2. The combination of a polishing-wheel, a standard, a carrier mounted on the standard, a series of spindles having their bearings in the carrier, a series of shafts arranged at right 90 angles to the spindles and geared thereto, a chuck on each shaft for engaging a sad-iron or like object, a worm-wheel on each spindle, and a worm arranged to engage the spindles as they are brought into polishing position, 95 with means for intermittently turning the carrier, substantially as described.

3. The combination in a polishing-machine, of a polishing-wheel, a carriage on which the shaft of the polishing-wheel is mounted, a 100 standard, a carrier mounted on the standard, a spindle on the carrier, a shaft mounted on the carrier at an angle to the spindle and geared thereto, a clutch on the shaft for engaging a sad-iron or like object, a cam on the 105 spindle, and a lever connected to the carriage and actuated by the cam for moving the carriage and its polishing-wheel toward and from the work carried by the chuck, substantially as described. 110

4. The combination in a polishing-machine, of a carriage, a polishing-wheel mounted on the carriage, a standard, a carrier on the standard, means for rotating the carrier, a series of shafts having chucks for engaging a sad-iron or like object to be polished, means for turning the shafts, and means for moving the polishing-wheel toward and from the work, 115 substantially as described.

5. The combination in a polishing-machine, 120 of a polishing-wheel, a carriage on which the wheel is mounted, a standard, a carrier mounted on the standard, means for intermittently rotating the carrier, a series of spindles having their bearings in the carrier, a shaft arranged at an angle above each spindle and geared thereto, a clutch for engaging a sad-iron or like object, means for releasing said clutch, and means for turning the spindles when the work is in position in respect to the 125 polishing-wheel, substantially as described. 130

6. The combination of a polishing-wheel, its shaft, a carriage on which the shaft is mounted, a standard, a carrier mounted on

the standard, a series of spindles having their bearings in the carrier, a cam on each spindle, and a lever actuated by the cams in rotation so as to move the polishing-wheel to and from the work, substantially as described.

5 7. The combination in a polishing-machine, of a polishing-wheel, a carrier, means for intermittently rotating the carrier, a series of spindles on the carrier, means for turning the 10 spindles when in position, a series of heads secured to the carrier, a shaft on each head, each shaft being geared to a spindle, a chuck on the end of the shaft for engaging the sad- 15 iron or other article to be polished, and a lever for actuating the chuck to release the iron, substantially as described.

8. The combination in a polishing-machine, of a base, a carriage, a driven shaft, a polishing-wheel mounted on said shaft, a bracket 20 projecting from the base, a standard secured to the bracket, a carrier mounted on the standard, a driven shaft, a star-wheel gear by which the carrier is driven from the said shaft, a series of spindles on the carrier, a 25 head above each spindle, a shaft in said head and geared to the spindles, chucks on the shafts for the reception of the article to be polished, a cam on each spindle, and connecting means by which the cams operate the 30 carriage on which the polishing-wheel is mounted, substantially as described.

9. The combination in a polishing-machine, of the base, a polishing-wheel, a bracket, a standard on the bracket, a carrier mounted 35 on the standard, a star-wheel secured to the carrier, a driven shaft, a worm on said shaft, a worm-wheel on the standard, a disk connected to the worm-wheel and having a pin which enters the slots in the star-wheel and 40 through which the carrier is given an intermittent rotary motion, a series of slots on the carrier, a shaft in each head, a chuck on the shaft for engaging the article to be polished,

and means for rotating one of the shafts when the iron is in line with the polishing-wheel, 45 substantially as described.

10. The combination in a polishing-machine, of the base, a polishing-wheel, a standard, a carrier mounted on the standard, a driven shaft, a worm, worm-wheel, and a 50 star-gear in one of said driving-shafts, a carrier by which an intermittent rotary motion is given to the carrier, a series of slots on the carrier, a shaft in each head, a chuck mounted in each shaft for engaging the article to 55 be polished, a series of spindles having their bearings in the carrier and geared to the said chuck-shaft, a worm-wheel on each spindle, a driven shaft, and a worm thereon engaging one of the worm-wheels when the article to 60 be polished is brought in line with the polishing-wheel, substantially as described.

11. The combination in a polishing-machine, of the base, a carriage, a weight for moving the carriage away from the work, a 65 standard, a carrier mounted on the standard, means for intermittently rotating the carrier, a series of spindles, a chuck-shaft geared to each spindle, means for rotating the spindle, a cam on each spindle, a lever pivoted to the 70 frame of the machine having one arm resting against the cam of the spindle in line with the rotating spindles, the other end of the said lever being connected to the carriage so as to move the polishing-wheel toward and 75 from the work as the work is turned, substantially as described.

In testimony whereof we have signed our names to this specification in the presence of two subscribing witnesses.
